UNITED STATES PATENT OFFICE.

FRANK BEHM, OF TOLEDO, OHIO.

BATH-CHAIR.

1,245,660.

Specification of Letters Patent.

Patented Nov. 6, 1917.

Application filed March 23, 1917. Serial No. 156,882.

To all whom it may concern:

Be it known that I, FRANK BEHM, a citizen of the United States, and a resident of Toledo, in the county of Lucas and State 5 of Ohio, have invented a certain new and useful Bath-Chair; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to a chair for use in a bath tub, and has for its object the provision of an improved article of this character which is simple and inexpensive in its construction, easily and quickly 20 adjustable to vary the height of the seat portion thereof and capable of being easily applied to or removed from a bath tub.

25 The invention is fully described in the following specification, and while, in its broader aspect, it is capable of embodiment in numerous forms, a preferred embodiment thereof is illustrated in the accompanying drawings, in which,—

Figure 1 is a side elevation of a bath tub 30 with a portion thereof broken away and with a chair embodying the invention mounted therein. Fig. 2 is an enlarged perspective view of a chair embodying the invention. Fig. 3 is a sectional elevation thereof, 35 and Fig. 4 is an enlarged perspective view of the seat member of the chair.

Referring to the drawings, 1, 1 designate 40 two uprights or standards which are rigidly connected in spaced parallel relation by rungs 2 or other suitable members, and co-operate therewith to form the frame or body of the chair. The upper end of each upright or standard 1 is provided or formed with a rearwardly projecting hook 3 for 45 engaging over the upper edge of a bath tub as shown in Fig. 1. The standards 1 are of suitable length to adapt their lower ends to rest on the tub bottom in slightly spaced relation to the side thereof by which carried 50 when the hooks 3 are in engagement with the upper edge of the side.

The seat member of the chair comprises, in the present instance, a board or plate 4 and a pair of cross bars 5, on which the 55 member 4 is mounted, said bars having their rear ends projected beyond the rear edge

of the member 4 and suitably spaced to fit between the standards 1, 1 and also between a respective set of studs or rungs at the inner sides of said standards. The studs 60 are designated 6 and the lower member of each set, whether it be a stud 6 or rung 2, is set forward a slight distance from the vertical plane of the upper stud or rung of the set, as clearly shown in Fig. 3. The 65 rungs 2 and studs 6 provide three vertically spaced sets in the present instance, with any set of which the seat bars 5 may be engaged, depending on the height at which it may be desired to place the seat. It is evident 70 that when the seat bars 5 are in engagement with a set of rungs or studs, such members coact with the bars to maintain the seat in horizontal position when the standards 1, 1 are in set-up engagement with the tub, 75 as shown in Fig. 1. Each seat bar 5 is provided at its lower rear edge with a shoulder or downwardly extending lug 7 to co-operate with the lower member of the supporting set of studs or rungs to prevent an accidental forward withdrawal of the bars from engagement therewith.

It is evident that I have provided a simple chair which is adapted for use within a bath tub, and that the seat member thereof 80 is capable of being easily and quickly adjusted to suit the height at which the person using the same desires to sit within the tub.

I wish it understood that my invention 85 is not limited to any specific construction or arrangement of the parts, as it is capable of numerous modifications without departing from the spirit of the claims.

Having thus described my invention, what 90 I claim as new and desire to secure by Letters Patent, is—

1. A chair of the class described, having spaced uprights for engaging over the rim of a bath tub and projecting down therein, 95 said standards having transversely projecting parts, and a seat having members projecting rearward therefrom between said parts and co-operating with said parts and standards to support the seat.

2. In a chair of the class described, a pair 100 of rigidly spaced standards adapted to be suspended within a bath tub, a seat having members projecting rearwardly therefrom, one at a side of each of said standards, and vertically spaced means carried by the standards for receiving said seat members there- 110

between and coöperating therewith to releasably hold the seat.

3. In a chair of the class described, a pair of rigidly spaced standards for engaging at their upper ends over the rim of a bath tub, a plurality of sets of members projecting transversely from each standard in vertically spaced relation with the members

of each set vertically spaced, and a seat having members projecting rearward therefrom for removable insertion between the members of a set to coöperate therewith to support the seat.

In testimony whereof, I have hereunto signed my name to this specification.

FRANK BEHM.
